UNITED STATES PATENT OFFICE.

WILLIAM W. JACKSON, OF PHILADELPHIA, PENNSYLVANIA, ASSIGNOR TO THE MATHER MANUFACTURING COMPANY, OF SAME PLACE.

DESIGN FOR A FONT OF PRINTING-TYPE.

SPECIFICATION forming part of Design No. 20,589, dated March 17, 1891.

Application filed February 11, 1891. Serial No. 381,086. Term of patent 7 years.

To all whom it may concern:

Be it known that I, WILLIAM W. JACKSON, a citizen of the United States, residing at Philadelphia, in the county of Philadelphia and State of Pennsylvania, have invented a certain new and useful Design for a Font of Printing-Type, of which the following is a full, clear, and exact description.

The accompanying drawing shows a font of type illustrating my design.

The leading features of my design are a font of type (especially adapted for chromatic printing) in which there are, first, projecting openings at the tops of the letters B, D, P, and R; second, beveled ascending lines of letters N, U, V, W, and Y; third, beveled descending lines of characters A, M, Q, R, S, and &; fourth, outline tops and beveled shading at bottoms of all the characters, and, fifth, ornamented justifiers and terminals.

The font illustrated is designed for printing in chromatic combinations, and there are the projecting openings a at the tops of the letters B, D, P, and R; also, the beveled ascending lines b in the letters N, U, V, W, and Y; also, the beveled descending lines c in the letters A, M, Q, R, S, and the &; also, the ornamented justifiers and numerals, and, finally, all the characters are made with outline tops d and beveled shading e at bottom. The numerals and other signs or characters combine the leading features already stated as far as possible.

What I claim is--

The design for a font of printing-type, substantially as shown and described.

In testimony whereof I have hereunto set my hand this 10th day of February, A. D. 1891.

WILLIAM W. JACKSON.
